UNITED STATES PATENT OFFICE.

HARRY ROZENSKA, OF DETROIT, MICHIGAN.

ASH-SIFTER.

1,336,538.

Specification of Letters Patent. Patented Apr. 13, 1920.

Application filed January 23, 1920. Serial No. 353,419.

To all whom it may concern:

Be it known that I, HARRY ROZENSKA, a citizen of Poland, residing at Detroit, in the county of Wayne and State of Michigan, have invented certain new and useful Improvements in Ash-Sifters, of which the following is a specification.

This invention relates to certain new and useful improvements in ash sifters, and the primary object of the invention is to provide an ash sifter of extremely efficient and durable construction so as to effectively separate ashes from coal in the well known and desirable manner.

5 The invention embodies broadly a hopper for reception of the ashes to be sifted, and an open-ended rotary sifting member tilt-able for filling and capable of being lowered and rotated for sifting of the finer particles therethrough into a suitable receptacle, a slide being provided for opening the open end of the rotary sifting member for permitting the coal to be delivered into a separate receptacle.

10 The invention is illustrated as to one embodiment thereof in the accompanying drawings wherein like reference characters indicate corresponding parts throughout the several views,

15 Fig. 1 is a longitudinal substantially central vertical sectional view of an ash sifter constructed in accordance with the present invention,

Fig. 2 is a vertical sectional view thereof taken substantially upon line II—II of Fig. 1,

Fig. 3 is a horizontal sectional view taken upon line III—III of Fig. 1 with parts removed,

20 Fig. 4 is a similar view taken upon line IV—IV of Fig. 1,

Fig. 5 is a view similar to Fig. 4 taken upon line V—V of Fig. 1,

Fig. 6 is a horizontal sectional view taken substantially upon line VI—VI of Fig. 2, and

Fig. 7 is a sectional fragmentary view illustrating the slide utilized for closing the open end of the rotary sifting member and the guide within which the shaft of said sifting member is shifted.

Referring more in detail to the several views, the present invention embodies an upright casing 5 preferably of substantially

rectangular form in horizontal section and supported upon suitable legs 6 which are provided with casters 7 at their lower ends. The upper end of the casing 5 is provided with a hinged cover or closure 8, and a hopper 9 is provided in the upper portion of the casing 5 directly beneath the cover 8. The hopper 9 is provided with a contracted outlet at its bottom portion, and this outlet is closed or opened as desired by means of a slide or gate 10 which is guided in suitable guides 11 which project rearwardly from the bottom portion of the hopper 9 in a substantially horizontal position. A handle 12 is carried by the slide 10 and extended rearwardly through an aperture 13 in the rear wall of the casing 5 so that a person may grasp said handle from the exterior of the casing for sliding the gate 10 to open the bottom outlet of the hopper 9 or to close the same at will.

75 A shaft 14 is normally disposed in a slight forwardly inclined position beneath the hopper 9 and is mounted in the rear wall of the casing 5 as at 15 so that the shaft is capable of being swung upwardly and downwardly as well as being capable of being rotated upon proper actuation of the handle 16 which is formed upon the rear end of said shaft 14 exteriorly of the casing 5.

The forward end of the shaft 14 is received within a vertical elongated guide 17 which is of arcuate form and rigidly secured at its ends as at 18 to the front wall of the casing 5. The lower end of the guide 17 is disposed so as to support the forward end of the shaft 14 for rotation at a slight forward incline and is extended upwardly where its upper end terminates a short distance beneath the bottom outlet of the hopper 9. The shaft 14 is part of a rotary sifting drum, the drum proper being formed by a screen member 19 of substantially tubular form and having an open forward end and a closed rear end, the screen 19 being supported in concentric relation to and surrounding the shaft 14 by means of a frame 20 and spiders 21.

100 A slide 22 is movable through a slot 23 provided in one side wall of the casing 5 so as to be moved inwardly for closing the forward open end of the screen drum 19 as best seen in Figs. 1 and 2; the slide 22 being provided with a longitudinal slot 24 sub-

stantially centrally and inwardly from its forward end so as to accommodate the shaft 14. The slide 22 is provided with a handle 25 positioned exteriorly of the casing 5 so that said slide may be manually moved inwardly or outwardly for closing or opening, as desired, the forward end of the drum 19.

An inclined chute 26 is rigidly mounted upon the front wall of the casing 5 and extends inwardly through an opening 27 provided in said front wall so that the inner end of the chute 26 is disposed beneath the open end of the drum 19. The lower end of the chute 26 is provided with a hook 28 adapted to receive the bail of a coal hod or other receptacle in the usual manner.

The bottom of the casing 5 is closed by means of a gate 29 which is hinged at its rear edge as at 30 adjacent to the rear wall of the casing 5 for vertical swinging movement, said gate 29 being held in its upper or closed position against the abutment 31 which is provided upon the lower edge of the front wall of the casing 5 beneath the chute 26, by means of a pair of strong leaf springs 32 whose rear ends are rigidly attached to the casing as at 33 rearwardly of the pivot 30, and whose forward ends bear against the under face of the gate 29 as best shown in Fig. 1. The gate 29 is preferably inclined and is provided with a handle 34 which may be lifted upwardly for the opening of the gate.

In operation, the cover 8 is raised for opening the upper portion of the casing so that the material to be sifted may be dumped into the hopper 9 and the drum 19 is then tilted upwardly by pressing downwardly upon the handle 16 so that the open forward end of said drum is disposed to receive the contents of the hopper 9 as indicated by dotted lines in Fig. 1. When the drum has been filled or partially filled with the material, the same is allowed to move downwardly to its normal full line position of Fig. 1 and the slide 22 is then moved inwardly so as to close the open forward end of the drum 19. The operator then turns the handle 16 for imparting rotation to the drum 19 and the finer particles are sifted through said drum in the usual manner onto the gate 29. A suitable receptacle may be placed between the front legs 6 of the sifter for receiving the finer sifted particles when the same are allowed to slide downwardly on the gate 29 by the opening of said gate through lifting the handle 34. The slide 22 is then withdrawn to substantially the position thereof as shown in Fig. 7, whereupon the larger particles are caused to move forwardly onto the chute 26 upon further rotation of the drum, the said larger particles being deposited in the receptacle which is hung upon the hook 28.

From the foregoing description, it is be-

lieved that the construction and operation of the present invention will be readily understood.

While the preferred embodiment of the invention is herein shown and described, it is nevertheless to be understood that minor changes may be made in the various parts as well as the combinations and arrangements thereof without departing from the spirit and scope of the invention as claimed.

What I claim as new is:—

1. An ash sifter comprising a casing having a hopper in the upper end thereof, a sifting drum journaled for rotation beneath the hopper normally at a slight forward inclination and tilttable upwardly to a rearward inclination, said sifting drum having an open end so that when the same is tilted upwardly the contents of said hopper may be deposited into the drum through its open end, means for opening and closing the forward end of said drum when the same is in its normal lowered position, and means for rotating said drum.

2. An ash sifter comprising a casing having a hopper in the upper end thereof, a sifting drum journaled for rotation beneath the hopper normally at a slight forward inclination and tilttable upwardly to a rearward inclination, said sifting drum having an open end so that when the same is tilted upwardly the contents of said hopper may be deposited into the drum through its open end, means for opening and closing the forward end of said drum when the same is in its normal lowered position, means for rotating said drum, and a receptacle supporting chute disposed beneath the forward end of said sifting drum.

3. In combination with a slightly inclined rotary sifting drum having an open forward end and tilttable to raise its forward end, a hopper disposed above said drum and having a bottom outlet for discharging its contents into the open end of the drum when the latter is tilted upwardly.

4. In an ash sifter, a casing, a hopper in the upper end of the casing having a bottom outlet, a vertical elongated shaft guide of arcuate form rigidly mounted upon the front wall of the casing, a sifting drum mounted beneath the hopper and including a shaft movable and rotatable in said guide and pivotally and rotatably mounted in the rear wall of the casing, said drum having an open forward end whereby, when the same is tilted upwardly to move the forward end of the drum shaft upwardly in said guide, the open forward end of said drum will be disposed to receive material discharged through the outlet of said hopper.

5. In an ash sifter, a casing, a hopper within the casing, a normally horizontal tilttable sifting drum journaled beneath the hopper and having an open end adapted to

- be moved adjacent the hopper to receive ashes from said hopper, and a controllable closure for the open end of the drum.
6. In an ash sifter, a casing, a hopper within the casing, a normally horizontal tiltable sifting drum journaled beneath the hopper and coöperating guide means for the tilting end of said drum carried by the drum and casing.
- 10 7. In an ash sifter, a casing, a hopper within the casing, a normally horizontal tiltable sifting drum journaled beneath the hopper and coöperating guide means for the tilting end of said drum carried by the
- drum and casing, the guide means carried by the casing adapted to limit the tilting movement of said drum.
8. In an ash sifter, a casing, a hopper within the casing, a normally horizontal tiltable sifting drum journaled beneath the hopper and coöperating guide means for the tilting end of said drum carried by the drum and casing, the guide means carried by said casing forming a bearing for one end of said drum.

In testimony whereof I affix my signature. 25

HARRY ROZENSKE.
